(57) **CLAIM**

The ornamental design for a keychain angel, as shown and described.

DESCRIPTION

FIG. 1 shows a front perceptive view of keychain angel showing my new design;

FIG. 2 is a rear elevational view;

FIG. 3 is a top plan view;

FIG. 4 is a front elevational view;

FIG. 5 is a side elevational view;

FIG. 6 is a bottom plan view;

FIG. 7 is a top plan view of a keychain angel showing a second embodiment of my new design;

FIG. 8 is a front elevational view of FIG. 7;

FIG. 9 is a side elevational view of FIG. 7; and,

FIG. 10 is a bottom plan view of FIG. 7.

The broken lines showing of wording is for illustrative purposes only and form no part of the claimed design.
